[57] CLAIM

The ornamental design for a laser beam manipulator for directionally controlling the transmission of a laser beam to a target, as shown and described.

DESCRIPTION

FIG. 1 is a front elevational view of a laser beam manipulator for directionally controlling the transmission of a laser beam to a target showing our new design;
FIG. 2 is a right side elevational view thereof;
FIG. 3 is a top plan view thereof, the rear elevation and the bottom plan view being identical;
FIG. 4 is a left side elevational view thereof;
FIG. 5 is a top front perspective view thereof.

FIG. 1

FIG. 2

FIG. 3

FIG. 4

FIG. 5
